UNITED STATES PATENT OFFICE.

CLIFTON HOLMES AND FLOYD E. BRINGLE, OF CUSHING, OKLAHOMA.

SEPARATING MACHINE.

Application filed August 6, 1923. Serial No. 656,047.

To all whom it may concern:

Be it known that CLIFTON HOLMES and FLOYD E. BRINGLE, citizens of the United States, residing at Cushing, in the county of Payne and State of Oklahoma, have invented new and useful Improvements in Separating Machines, of which the following is a specification.

This invention relates to a separating machine for liquids, the general object of the invention being to provide a centrifugal drum with means for feeding thereinto the liquid to be separated and exhausting therefrom the heavier liquid or liquid containing sediment and other means for exhausting therefrom the lighter liquids.

A further object of the invention is to arrange the inlet and exhaust means in the shaft which supports the drum.

A still further object of the invention is to provide valve means for controlling the discharge of the heavier liquids.

Another object of the invention is to provide means for dividing the drum into chambers with means for feeding the liquid to be separated into the chambers and for discharging the heavier liquids from the outer parts of said chambers.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a side view of the invention.

Figure 2 is a longitudinal sectional view.

Figure 3 is an end view.

Figure 4 is a section on line 4-4 of Figure 1.

Figure 5 is a section on line 5-5 of Figure 1.

Figure 6 is a section on line 6-6 of Figure 1.

The remaining figures are detail views. In these views 1 indicates a base which supports the journals 2 for the hollow shaft 3. A drum 4 is supported by the shaft between the upright parts of the base. Brackets 5 are located at the sides of the base, these brackets supporting the stuffing boxes

6, 7 and 8 through which the shaft and its associated parts pass. Each box comprises a cylinder 9 having an internal annular groove 10 from which leads a passage 11 which may be formed in a part of the supporting bracket. Plates 12 are connected with the ends of the cylinder and caps 13 fit in the ends of the cylinder and are provided with heads 14 which are bolted to the plates 12 so that these caps will compress the packing material 15 and thus make a tight joint between the grooved part of the cylinder and the shaft. The hollow shaft is provided with a small bore 16 which extends from one end of the shaft to a point adjacent its center and with a large bore 17 which extends from the opposite end of the shaft to a point adjacent the center. Thus a solid part is located between the inner ends of the bores. Transverse holes 18 connect the inner end of bore 16 with the interior of the drum and transverse holes 19 connect the bore 16 with a groove 20 formed in the shaft and which is arranged to coincide with the groove 10 in the packing box 8. The outer end of the bore 16 is closed by a plug 21. A spirally grooved shaft 22 is arranged in the bore 17 of the hollow shaft, and is held therein by the set screw 22', the ends of the spiral grooves 23 communicating with annular grooves 24 and 25 formed in the shaft 22. The groove 24 communicates with a groove 24' formed in the shaft 3 by means of the holes 24" in said shaft. The groove 24' is located in the stuffing box 6 and coincides with the groove 10 in such box and the groove 25 registers with holes 26 formed in the shaft 3, these holes 26 being screw threaded to receive the screw threaded ends of pipes 27 which are arranged in the drum and have their outer ends connected with a hollow ring 28 which is perforated, as shown at 29, and which passes through holes in partition plates 30 in the drum. The inner ends of these plates terminate an appreciable distance from the center of the drum. These plates divide the drum into a plurality of chambers. The spiral shaft 22 is provided with a bore 31, the inner end of which communicates with the transverse holes 32 made in the spiral shaft and these holes 32 register with holes 33 formed in the shaft 3 and to which the inner ends of pipes 34 are connected. These pipes are connected to the ring 28, as shown at 35, in any de-

sired manner, so that they will be strengthened by said ring and their outer ends terminate short of the outer ends of the chambers in the drum which are formed by the 5 partition plate. This arrangement of parts places the interior of the drum in communication with the bore 31 of the spiral shaft. The shaft 3 is provided with a screw threaded socket to receive the reduced screw 10 threaded end of a stub shaft 36, which, when in place, abuts the end of the spiral shaft. This end of the stub shaft is provided with a valve seat 37 which is engaged by the valve 38, the stem 39 of which passes 15 through the stub shaft and through the guide 40 carried by said shaft. This stub shaft has transverse holes 41 formed therein which communicate with the bore of the shaft and with an annular groove 42 formed 20 in the shaft, this groove 42 being located in the stuffing box 7 and coincides with the groove of said box. A packing gland 43 is placed at the end of the stub shaft to prevent leakage around the valve stem and 25 said valve stem is connected by the yoke 44 and the follower 45 with a two-part lever 46 which is pivotally supported on a standard 47 and is provided with the usual means for holding it in adjusted position. A 30 spring 48 tends to hold the valve in closed position and the packing gland tightly against the end of the shaft 36.

A pulley 49 is connected with the shaft 3 and the passages 11 are controlled by valves 35 50.

The liquid to be treated is forced into the passage 11 of box 6 in any suitable manner. This liquid will pass from the box through the groove 24' and the holes 24'' of shaft 40 3 into the groove 24 of the spiral shaft 22 and will pass through the spiral grooves in said shaft to the groove 25 and will pass from said groove 25 through the holes 26 in shaft 3 into the pipes 27 to the ring 28 45 and through the perforations 29 therein into the drum. The rotary movement of the drum will cause the heavier liquids or liquids containing sediment to occupy the outer parts of the chambers in the drum, the 50 lighter liquids being located adjacent the center of the drum. These lighter liquids will therefore pass through the holes 18 into the bore 16 of the shaft 3 and will pass from said bore through the holes 19 into the groove 20 and will thus flow out of the passage 11 of the box 8. This passage 11 may be connected with any suitable container for holding the lighter liquids. The heavier liquids will pass through the pipes 34 from the chambers into the bore 31 of the spiral shaft 22 through the holes 33 and 32 and such liquids will pass from said bore 31, provided the valve is open, into the bore of the shaft 4 and will pass from said bore 60 through the holes 41 and groove 42 into the

box 7 and thus escape through the passage 11 in said box. Thus the liquid to be treated is fed through the hollow shaft and its associated parts into the drum, the lighter liquids escaping through another portion of the hollow shaft and the heavier liquids 70 passing through the spiral shaft which is carried by the hollow shaft and through the stub shaft to the box 7. By manipulating the lever 46 the escape of the heavier liquids 75 can be controlled and the valves 50 also provide means for controlling the flow of liquid into and out of the device. The parts can be provided with any form of lubricating means and the apparatus can be 80 driven from any suitable source of power.

This machine can be used for treating liquids of all kinds and it may also be used for removing sediment and the like from lubricating oil which has been used for lubricating purposes and contains grit and the like which will make it useless for further lubrication unless cleaned. After running such oil through the apparatus it may be 90 used again. It can also be used for cleaning crude oil from foreign matter though we do not wish to be limited to the use to which the invention is put.

It is thought from the foregoing description that the advantages and novel features of the invention will be readily apparent.

We desire it to be understood that we may make changes in the construction and in the combination and arrangement of the several parts, provided that such changes fall within the scope of the appended claims.

What we claim is:

1. A separator of the class described comprising a drum, a shaft supporting the same, means for rotatably supporting the shaft, means for rotating the shaft, said shaft having a passage therein having its inner end in communication with the drum and a spiral passage therein which is separated from the first passage and which has one end also in communication with the drum.

2. A separator of the class described comprising a drum, a shaft supporting the same, means for rotatably supporting the shaft, means for rotating the shaft, said shaft being hollow for a portion of its length, a hollow member in the shaft and having a spiral groove in its outer circumference, pipes carried by the shaft and arranged within the drum and having their inner ends in communication with the spiral groove, other pipes carried by the shaft and arranged within the drum and having their inner ends in communication with the bore of the hollow member and delivery means connected with the spiral groove and with the bore of the hollow member and means for feeding liquid to the drum.

3. A separator of the class described comprising a drum, a shaft supporting the

- same, means for rotatably supporting the shaft, means for rotating the shaft, said shaft being hollow for a portion of its length, a hollow member in the shaft and having a spiral groove in its outer circumference, pipes carried by the shaft and arranged within the drum and having their inner ends in communication with the spiral groove, other pipes carried by the shaft and arranged within the drum and having their inner ends in communication with the bore of the hollow member and delivery means connected with the spiral groove and with the bore of the hollow member and means 15 for feeding liquid to the drum, such means including a passage in the shaft and having one end communicating with the interior of the drum.
4. A separator of the class described comprising a hollow shaft having a small bore in one part and a large bore in another part, a drum carried by the shaft, said shaft having holes therein for placing the bores in communication with the interior of the 20 drum, a spirally grooved shaft in the large bore, the inner ends of said spiral grooves being in communication with one set of holes in the shaft, feeding means connected with the other ends of the spiral grooves, said 25 spirally grooved shaft having a bore, pipes located in the drum and having their inner ends in communication with said bore in the spirally grooved shaft and delivery means connected with said bore of the spirally 30 grooved shaft and the small bore of the main shaft, means for supporting the main shaft and means for rotating the same.
5. A separator of the class described comprising a shaft, means for supporting the same, means for rotating the same, a drum connected with the shaft, said shaft having a small bore and a large bore, the inner ends of which are separated, said shafts having 35 holes therein for placing the small bore in communication with the center of the shaft, delivery means connected with said small bore, a spirally grooved shaft in the large bore, said shaft having holes therein for placing the inner ends of said spiral grooves 40 in communication with the interior of the drum, feeding means connected with the other ends of said spiral grooves, said spirally 45 grooved shaft having a bore, pipes located in the drum and carried by the main shaft and having their inner ends in communication with the bore of the said spirally 50 grooved shaft, a stub shaft connected with the main shaft and having a bore therein in communication with the bore of the spiral shaft, delivery means connected with the bore of the stub shaft and valve means carried by the stub shaft for controlling the 55 passage of the liquid through the bore thereof.
7. A separator of the class described comprising a shaft, means for supporting the same, means for rotating the same, a drum carried by the shaft, pipes in the drum and connected with the shaft, a perforated ring connected with the ends of said pipes, said 60 shaft having a feed passage therein in communication with the inner ends of the pipes, said shaft also having a passage therein in communication with the center part of the drum, delivery means for said passage, discharge pipes in the drum and carried by the 65 shaft, a discharge passage in the shaft connected with the inner ends of said pipes and discharge means connected with the said 70 discharge passage.
- In testimony whereof we affix our signatures.

CLIFTON HOLMES,
FLOYD E. BRINGLE.
